UNITED STATES PATENT OFFICE.

WILLIAM J. KEHOE, OF WASHINGTON, DISTRICT OF COLUMBIA.

RECORDING SPEECH.

No. 908,575.

Specification of Letters Patent.

Patented Jan. 5, 1908.

Application filed June 9, 1908. Serial No. 437,554.

To all whom it may concern:

Be it known that I, WILLIAM J. KEHOE, a citizen of the United States, residing in Washington, District of Columbia, have invented certain Improvements in Recording Speech, of which the following is a clear, full, and exact specification.

My invention relates to a method of recording speech, and is designed to lessen the number of depressions required; in said recording, so that the system or method may be more rapidly carried out with the proper mechanism.

The method consists in providing a series of characters preferably ten in number and either of arbitrary configuration or of ordinary marks, as dots and dashes, dividing the said characters into two parallel sets, the first set containing preferably five dashes and the second set five dots, and in the different combinations with each other they represent vowels, consonants, numerals, etc.; and thereby it is possible by this system or method to write words in parallel groups or to designate syllables with as many characters as may be required by the system for a syllable, a word, or figure, which are struck simultaneously or alternately, and by reason of the special value or order given the said characters, I am enabled to write or print stenographically or in an abbreviated form, susceptible of being easily read, any word, sound, or combination of sounds that may be produced by the human voice in speaking.

It is essential to the practical carrying out of this method that means be provided whereby the characters employed may be produced substantially in parallel groups and such means have been covered by a patent granted me, September 10, 1907, Serial Number 865,910.

Other features enter into this invention and the arrangements of parts and combination of devices are hereinafter set forth and particularly pointed out in the appended claim.

In the drawings I have illustrated a machine susceptible of use in variable ways for carrying out my peculiar method, which being, as I believe, the most rapid and satisfactory one by which it can be operated, and I claim such a method in this application.

Attempts have hitherto been made to produce a method or system and mechanical means by which speech or language might be

stenographically recorded, but in every proposed plan, so far as I am aware, each separate word is designated by a greater space or interval between it and the adjacent word as 60 compared with the distance of the characters composing a word; but by my method each word commencing with a consonant is always indicated with the same designed marking character; and the word beginning with a 65 vowel may be designated by a different character, such as a dot; furthermore, each syllable or word is spaced an equal distance apart, and when desired a new paragraph and punctuation marks may be designated 70 by a larger space than is used between the syllables making up a word. I have, however, adopted letters of the alphabet to represent the different finger-keys of the stenographic machine and the letters of the right 75 hand finger keys to correspond precisely to those of the left hand finger keys, or in other words, the finger-keys for the thumb of the two hands are represented in the manual used in my method by D, the first 80 finger-key to be represented by the letter N, the second finger-key by R, the third finger-key by T, and the fourth finger-key by S, and the corresponding characters of the respective finger-keys to be printed above one 85 another, that is, D, both dot and dash are placed on the lower-most portion of the paper tape and N, R, T, and S are placed above each other in their respective order, and such a result will be seen from the illustration, shown in Fig. 3 of the drawings.

When writing by this method the right hand finger-keys have dashes for their marking characters and are struck simultaneously with the dot when the word that begins with 95 a consonant is recorded. The left hand finger-keys have dots for their marking characters and may either be struck simultaneously or alternately in combination with the dashes and with each other, and are used to 100 begin all words commencing with a vowel sound.

The paper tape before mentioned moves transversely over the two sets of marking characters and between an inked ribbon and 105 impression roller which is actuated by the proper feed mechanism which will be set forth in a subsequent part of this specification.

Referring now to the drawings; Figure 1 110 is a longitudinal central sectional view taken on line Z—Z of Fig. 2 showing some parts in

elevation. Fig. 2 is a plan view illustrating my improved stenographic machine. Fig. 3 is a view of a printed slip of tape as produced by this machine when the ten keys are struck simultaneously in pairs and in succession. Fig. 4 is a view of a printed slip of tape and translation. Fig. 5 is a view of one of the finger-keys or type bars and fulcrums for keeping the marking characters thereon in alignment at its printing point. Fig. 6 is a diagrammatical view illustrating the relative position of the paper tape and the inked ribbon with other parts.

In the several views similar parts are designated by similar numerals of reference.

The numeral 1 designates as an entirety a stenographic machine having two sets of independent type bars or finger-keys as indicated by the letters of reference A and B, each having characters X at the inner end, thereof of any suitable form for producing the marking effect upon the paper tape, and in this instance I have shown dots and dashes for their marking characters as these are simple and are therefore preferred.

The type bars or finger-keys are fulcrumed upon a plate 3 as shown very clearly at Y in Figs. 1 and 2, and having their inner ends resting upon a piece of felt 4, which renders said type bars noiseless when operated upon; it also limits the downward movement of same. The springs 6 serve to keep the inner ends of the type bars in the lower-most position and are fastened in holes through the plate 3. This plate supports a space actuating device 7, by means of two posts 8, to which this spacing device is pivoted. Said spacing device 7 overlies the type bars at their inner ends, and is provided with a piece 30 of felt 9, also for the purpose of eliminating all the noise or metallic sounds of this machine as much as possible so that it can be used where quietness is desirable, as in court rooms.

The above-mentioned spacing device is held down upon the type bars by an adjustable spring 11, which is fastened to the plate 3, or by any other suitable means. Upon this device is carried a pivoted spring pressed 45 pawl 12, which engages a ratchet wheel 13, and at each depression of any of the marking keys, the spacing device is raised such a distance as to move the pawl 12 one tooth upon the ratchet-wheel 13, so that as the marking 50 keys descend and the spacing device with it, the rubber impression roller 14 turns and pulls the paper tape 14" a distance such as to print impressions upon the paper tape in parallel groups and if the two sets of marking characters be impressed on the paper tape simultaneously and repeatedly the result will be shown in Fig. 3.

It will be observed that by the use of this instrument the spacing device 7 causes no marking effect upon the paper tape and is

only for the purpose of distinguishing entirely new paragraphs, punctuations, etc. Further, it must be understood that it is not essential to make use of the spacing device between words as is now practiced.

Referring to the drawings and particularly to Fig. 6, it will be noticed that an inked ribbon 15', at each movement of either the spacing device or any of the type bars moves slowly along underneath the rubber impression roller 14. The rubber impression roller is fastened or mounted upon a metal sleeve 15", which revolves slowly upon an axial 16, supported by the frame work or standard 16', held in place by screws to the base plate of the machine. The axial 16 supports an arm 16" which carries spur-gears 18, and 19', the latter meshing with the gear 19 integral with the sleeve 15", and by this arrangement of gears imparting the desired motion to the reel spur-gears 20 and 21 respectively, which are greater in diameter, and consequently would revolve very slowly for the purpose of detaining the shifting movement of the inked ribbon in winding 70 from one reel to another. When the inked ribbon 15' is wound all on reel 22, its direction is reversed, this being accomplished by throwing the spur-gear 18 to the right to mesh with the larger reel spur-gear 20, and 75 thereby winding said ribbon on reel 22.

The paper tape is supplied from a paper roll, not shown, and is supported between the bifurcated bracket 23, secured to the left side of the machine by a standard 24. This 80 bracket supports upon its axial 25, a reel 26, upon which is wound the loose end of the paper tape as it is delivered from the machine, it being at the same time a convenience for the operator can at any time pick 85 up the machine with the work already accomplished and transfer the same to any locality.

Directly in line with the bracket 23, is a paper guide 27, and a spring pressed friction 90 roller 28, these members being suspended from a bracket 29 fastened over the reel 22, upon the base of the machine as shown in Fig. 2. The paper is guided between the rubber impression roller 14, and the aforesaid 95 friction roller, the latter bearing against the upper surface, thus assuring of no slipping of the paper while passing between the two rollers.

In Fig. 5 I have illustrated a perspective 100 view of one of the type bars, which is an improved self-adjusting type bar in its bearing and fulcrum. Referring to the drawings, it will be observed that the type bar is constructed preferably of two flattened rods 105 30 and 31, which are secured together at 32 and 33, as indicated, by any suitable means such as soldering or riveting. The flattened rods 110 diverge from the points of connection, thereby forming a widened portion, making suit- 115 30 and 31, as indicated, by any suitable means such as soldering or riveting. The flattened rods 110 diverge from the points of connection, thereby forming a widened portion, making suit- 120 30 and 31, as indicated, by any suitable means such as soldering or riveting. The flattened rods 110 diverge from the points of connection, thereby forming a widened portion, making suit- 125 30 and 31, as indicated, by any suitable means such as soldering or riveting. The flattened rods 110 diverge from the points of connection, thereby forming a widened portion, making suit- 130 30 and 31, as indicated, by any suitable means such as soldering or riveting. The flattened rods 110 diverge from the points of connection, thereby forming a widened portion, making suit-

able supporting means for balancing the type bars upon vertical fulcrum pins 34 and 35, conveniently fastened to their respective rods. The material used should be of sufficient spring quality, such as spring brass or cold rolled steel, but any other suitable material may be used.

The fulcrum pins 34 and 35 must be so distanced that they do not match or correspond 10 with the centers of the tapered holes W in plate 3, as indicated in Fig. 5, of the drawings, that is to say, the pins must be a greater distance apart as compared with the holes in the plate 3, and when inserted into 15 the holes the vertical pins have their fulcrum or bearing at the extreme outer portion of the holes in said plate, so if any wear takes place within a short period the pins will consequently follow the wear due to the spring 20 in the flat rods 30 and 31 of the type bars. As this self-adjusting type bar is not a part 25 of my method or system of writing it will be unnecessary to describe it any further, as various modifications may be made and it is separate subject matter.

Having thus described my invention in this specification, what I claim, is:

The method of printing grouped characters for stenographic recording, which consists in alining dissimilar arbitrary markings 30 representing consonant and vowel sounds respectively, across a tape, designating a word commencing with a consonant by a dash for a marking character of the right-hand keys, and designating a word commencing with a 35 vowel by a dot for a marking character of the left-hand keys, and completing a word by a combination of both characters, the latter being in closer proximity to the first characters of a recorded word than to the first characters of a preceding word, thereby indicating a distinction of words by a greater distance between them without the aid of extra spacing of any special finger key, substantially as described.

WILLIAM J. KEHOE.
